Primary Examiner — Katherine Glennon(74) *Attorney, Agent, or Firm* — RatnerPrestia(57) **CLAIM**

The ornamental design for a watchcase, as shown and described.

DESCRIPTION

FIG. 1 is a front perspective view of a watchcase showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a rear perspective view thereof.

The broken lines depict portions of a watchcase that form no part of the claimed design.

1 Claim, 6 Drawing Sheets(56)
